UNITED STATES PATENT OFFICE.

JOHN H. LEWIS, OF RHINELANDER, WISCONSIN.

NECK-YOKE LOCK.

Application filed July 18, 1923. Serial No. 652,405.

To all whom it may concern:

Be it known that I, JOHN H. LEWIS, a citizen of the United States, residing at Rhinelander, in the county of Oneida and 5 State of Wisconsin, have invented a new and useful Neck-Yoke Lock, of which the following is a specification.

The present invention has reference to neck yokes and aims to provide a novel form 10 of neck yoke which may be readily and easily secured to the outer extremity of a wagon pole.

The primary object of the invention is to provide means for locking the yoke to the 15 wagon pole to insure against the same becoming displaced therefrom, the locking means being such as to permit the ready application of the yoke.

A further object of the invention is to 20 provide a device of this character which may be readily and easily positioned on the usual wagon poles now in use, eliminating the necessity of making extensive alterations in the pole construction to mount the 25 device.

With the foregoing and other objects in view which will appear as the description proceeds, the invention resides in the combination and arrangement of parts and in 30 the details of construction hereinafter described and claimed, it being understood that changes in the precise embodiment of the invention herein disclosed, may be made within the scope of what is claimed, without departing from the spirit of the invention. 35

Referring to the drawing:

Figure 1 is a side elevational view of a pole disclosing a yoke as secured thereto;

Figure 2 is a fragmental front elevational 40 view thereof.

Figure 3 is an enlarged detail view of the pole and yoke locking means, portions of the pole and yoke being shown in section.

Referring to the drawing in detail, the 45 reference character 5 designates a wagon pole which is tapered towards its outer or free end in the usual manner. An opening 6 is formed in the free end of the pole 5 and accommodates the sliding bolt 7 which is 50 formed with a threaded opening to accommodate the controlling arm 8 by means of which the bolt 7 may be moved to its active and inactive position, there being provided a coiled spring 9 within the opening and 55 engaging the bolt 7 for normally urging the bolt 7 to the limit of its outward movement.

The lock also embodies a lower section 10 and an upper section 11, each section being curved transversely of its length so that the same may fit over the pole 5. The bolt 12 60 passes through the sections 10 and 11 and through a suitable opening formed in the pole, which bolt is adapted to clamp the sections 10 and 11 against movement.

The outer extremity of the lower section 10 extends upwardly in spaced relation with the free end of the pole 5, where the same is provided with an opening 13 to accommodate the reduced end 14 of the sliding bolt 7, thereby providing a keeper for the 70 sliding bolt when the sliding bolt is in its inactive or locking position.

As shown, the upper section 11 has one end thereof extending upwardly at 15 and downwardly at 16 to provide an abutting surface to be engaged by the yoke 17 to relieve the bolt 7 of the strain usually directed to the pole 5, when the draft animals which are hitched to the pole hold back as in the case of backing the vehicle. The downwardly 80 extended portion 16 has a threaded extremity 18 passing through an opening in the lower section 10 where a nut 19 is positioned thereon securing the upper and lower sections together. 85

Supported by the yoke 17 is a band 20 which is secured to the yoke in any suitable manner, the ends 21 forming a part of the band being supplied with openings to accommodate the sliding bolt 7 so that when the yoke is positioned, as shown by figure 90 3 of the drawing, the yoke will be securely locked against displacement from the pole 5.

What is claimed as new is:—

1. In combination with a wagon pole having an opening formed in one end thereof, a spring pressed bolt movable within the opening, a locking device including an upper section and a lower section, the lower section having an upwardly extended end lying in spaced relation with one end of the pole and having an opening, a neck yoke having a band formed with extensions, the extensions having openings to receive the bolt, the free end of the bolt adapted to pass into the opening of the upwardly extended end of the lower section, and said yoke adapted to engage the upper section to restrict movement of the yoke. 100

2. In a device of the character described, a wagon pole having an opening formed in one end thereof, a spring pressed bolt mov- 110

able within the opening, a locking device including an upper section and a lower section, said lower section having an upwardly extended portion disposed in spaced relation 5 with the free end of the pole, said upper section having an upwardly and downwardly extended portion, means for securing the downwardly extended portion to the lower section, said upwardly extended portion of the upper section providing an abutment, a neck yoke having means cooperating with the sliding bolt to secure the neck yoke

to the wagon pole, and said neck yoke adapted to engage the upwardly and downwardly extended portion of the upper section, to 15 restrict movement of the yoke.

In testimony that I claim the foregoing as my own, I have hereto affixed my signature in the presence of two witnesses.

JOHN H. LEWIS.
